UNITED STATES PATENT OFFICE.

EDWARD L. CADWELL AND WILLIAM H. CADWELL, OF DETROIT, MICHIGAN.

CUSPIDOR.

SPECIFICATION forming part of Letters Patent No. 701,291, dated June 3, 1902.

Application filed March 17, 1902. Serial No. 98,534. (No model.)

To all whom it may concern:

Be it known that we, EDWARD L. CADWELL and WILLIAM H. CADWELL, citizens of the United States of America, residing at Detroit, in the county of Wayne and State of Michigan, have invented certain new and useful Improvements in Cuspidors, of which the following is a specification, reference being had therein to the accompanying drawings.

Our invention relates to improvements in cuspidors for railway and other cars and conveyances, and more especially to that class of such devices which are set in the floor and operate to discharge their contents there-through; and its object is to provide a cuspidor which is so constructed that the closing of the cover operates to dump the contents through its open bottom and the opening of the cover closes the bottom to form a receptacle in the floor, said opening being always closed in either position of the parts to prevent the ingress of dust or dirt from the outside.

A further object of this construction is to provide a device which will not become clogged by dirt, has few parts, is simple, cheap, and not liable to get out of order.

To this end the invention consists in securing within an opening in the floor of the car a casing flush with the surface of the floor and within this casing pivotally securing a casting, forming the bowl or bottom of the cuspidor, which bottom is extended upward at one side and hinged to the cover, which cover lies on the surface of the floor and is guided only by the extended portion of the bowl moving within the casing; and the invention further consists in the peculiar manner in which the bowl is pivoted and in the construction and combination of parts, all as hereinafter more fully described, reference being had to the accompanying drawings, in which—

Figure 1 is a longitudinal vertical section of a device embodying our invention on the line 1 1 of Fig. 2, and Fig. 2 is a plan view of the same with parts broken away to show the construction.

A is a rectangular casing forming the body of the cuspidor, which casing consists of four perpendicular walls extended downward through an opening in the floor B and held

therein by a flange A' at the upper end of the casing, which flange engages a recess in the floor and is secured therein flush with the surface thereof by screws. Within said casing is pivotally secured the casting C, forming the bottom or bowl of the cuspidor, which casting consists of a curved bottom portion C', which is of a width to fit within the casing A and is provided with flanges C², forming the sides of the bowl, the portion C' being extended upward to the top of the casing A, where it is connected by hinges D to the cover E of the cuspidor.

The cover E lies upon the surface of the floor and is adapted to be moved longitudinally over the top of the casing A to close the same, said cover being guided in such movement by the upper end of the casting C moving between the side walls of the casing, and therefore no ways or other guides on the floor are necessary.

A rod F, passing through the side walls of the casing A, extends across the casing beneath the bottom C' and forms a pivot for the bowl, which is held in engagement therewith and permitted to slide thereon by means of the guide-loops G, which consist of rods extending parallel with the bottom C' and at a sufficient distance therefrom to allow the rod F to move freely between said guides and the bottom C' and are turned at right angles near their ends, which ends are secured in openings in said bottom. The bowl or casting C is thus pivoted to turn upon the rod F and also has a longitudinal or sliding movement thereon, so that when it is turned to the position shown in dotted lines in Fig. 1, by the closing of the cover, said bowl will slide on the rod F and will not raise the cover from the floor, but will tend by its added weight to hold said cover down. A rib H on the inner side of one of the walls of the casing A is engaged by the lower end of the bottom C' when the cuspidor is open and prevents the forward end of the cover and the attached bowl from being lifted and also covers the space between the wall and bowl and prevents the dirt, &c., from getting between the same and preventing the bottom from closing tightly.

What we claim as our invention is—

1. In a cuspidor, the combination with the car-floor having an opening; of a longitudi-

nally-movable cover to close said opening and a bowl pivoted to turn beneath the opening and extended upward therein and hinged to the cover whereby the cover is guided by the engagement of the bowl with the side of the opening in the floor.

2. In a cuspidor, the combination with a casing forming the body of the cuspidor and open at its top and bottom, of a longitudinally-movable cover to close the upper end of said casing, and a pivoted bowl to close the lower end of said casing having a portion extended upward and hinged to the cover and adapted to guide the same.

15 3. In a cuspidor, the combination with a casing open at its top and bottom, of a longitudinally-movable cover to close the upper end of said casing, a bowl to close the lower end of the casing, having a portion extended 20 upward and hinged to the cover, and a pivot upon which said bowl is free to turn and to slide.

4. In a cuspidor, the combination with a rectangular casing forming the body of the 25 cuspidor and open at its top and bottom, of a cover to close the top of said casing, a bowl within said casing, having a portion extend-

ed upward and hinged to said cover, a rod extending transversely across the casing and a guide-loop on said bowl engaging said rod 30 and holding the bowl in engagement therewith.

5. In a cuspidor, the combination with a rectangular casing forming the body of the cuspidor and open at its top and bottom, of a longitudinally-movable cover to close the upper end of said casing, a bowl having a curved bottom portion extended upward to the top of the casing and side flanges engaging the side wall of the casing, hinges connecting the upper end of said bottom portion with said cover, a rod extending through the walls of the casing and transversely across the same, guide-loops on the bottom portion of the bowl engaging said rod, and a rib on 45 the casing forming a stop to engage the lower end of said bottom portion.

In testimony whereof we affix our signatures in presence of two witnesses.

EDWARD L. CADWELL.
WILLIAM H. CADWELL.
